UNITED STATES PATENT OFFICE

JOHN NIVER SCISM, OF HARTFORD, CONNECTICUT

DROP HAMMER

Application filed July 14, 1923. Serial No. 651,602.

My invention relates to drop hammers, and particularly to what is known in the art as board drop hammers.

Such drop hammers stand high above the floor line, and include a heavy head which slides vertically between two uprights or guides. A board is attached to the head and extends upwardly between rolls which are arranged in the frame of the drop hammer to move into and out of engagement with the board. When a hammer is in use, the rolls are driven continually, and by means of suitable linkages the rolls are caused to engage frictionally the board, whereby the head is raised the desired distance. Thereupon, the rolls are moved away from the board, and the head is allowed to fall freely under the forces of gravity. The rolls heretofore have been driven by belts running from line shafting, and, as the hammer is raised and dropped, there are intermittent strains or jerks transmitted to the belts and shafting. From the shafting the strains are usually transmitted to some part of the building, to which the shafting is attached, as well as to the hammer itself. To accommodate these strains guide rods are generally connected from the hammer to some part of the building; however, such bracing is not always possible and when it is not possible an excessive side strain is placed upon the uprights of the hammer. Therefore, the hammer uprights have to be made exceedingly strong, heavy and expensive.

I have mentioned in my application Serial No. 636,463, concerning "a driving mechanism for drop hammer", that it is very objectionable to have these intermittent strains or jerks transmitted to the building. In the following specification I mention other objections to the use of line shafting for driving drop hammers.

As an example of these objections, a long line of shafting is often difficult to install where it is needed in a shop, because the roof members, or trusses, or pillars of the building are not always adapted for such installation. A line of shafting and its associated belting often obstruct and close passageways, and in general interfere with the installation

or operation of other machinery and overhead construction. In case of a breakdown on some part of the line of shafting, several machines would, obviously, become temporarily idle.

The object of the present invention is to provide a drop hammer having an individual electric motor and driving mechanism, whereby each hammer is operated independently. Such a hammer may be installed as a unit within a minimum of space, and upon a small individual foundation.

When a drop hammer is being operated the blows struck by the head cause very severe shocks and vibrations, and a further object of my invention is to provide a cushioned motor drive which may be placed closely to or immediately upon a drop hammer. In so cushioning and so placing the motor drive, the said shocks and vibrations will be greatly absorbed.

Another object of the invention is to provide a motor mounting and a motor drive which will permit one or more pairs of rolls to be driven by direct gearing, as presently will be described, or by pulleys as shown in my application Serial No. 636,463.

In the accompanying drawings Fig. 1 is a view, partly in side elevation and partly in vertical section, illustrating a drop hammer with an electric motor attached to its frame and geared to a shaft which extends to the top of the machine for driving the board-elevating rolls. Fig. 2 is a plan view of the drop hammer. Fig. 3 is a fragmentary view, partly in front elevation, and partly in vertical section, showing the upper portion of the machine. Fig. 4 is a fragmentary view, partly in vertical section and partly in side elevation, showing a modification of the driving gears for the device. Fig. 5 is a view in cross section of the small pinion shown in the upper portion of Fig. 1, which pinion controls the pressure of the two front rolls upon the board. Fig. 6 is a rear elevation of the hammer, illustrating the manner in which the improved driving mechanism is supported in accordance with my invention. Fig. 7 is a fragmentary view, showing in end elevation a portion of the motor mounting shown

in Fig. 6. Fig. 8 is a fragmentary view in plan, showing one of the pair of levers which is pivoted to the machine frame for supporting the motor. Fig. 9 is a plan, to larger scale, of a lock washer, and shows in cross section the tension rod which appears in Figs. 6 and 7. Fig. 10 illustrates in side elevation a modified motor mounting, and cushioning means therefor. Fig. 11 is a view in rear elevation of the modification shown in Fig. 10. Fig. 12 is a fragmentary view, showing in elevation a spring which may serve as the cushioning means of the structure shown in Figs. 10 and 11. Fig. 13 illustrates in side elevation another form of a cushioned motor support; and Fig. 14 is a rear elevation of the same. Fig. 15 is a fragmentary view of one of the levers which secures the motor support to the machine frame, and which cooperates with other motor-supporting elements, as shown in Figs. 6 and 19. Fig. 16 is a fragmentary view of a portion of the motor support which is shown in Fig. 19. Fig. 17 is a fragmentary view in plan from above, showing a pin connection which will presently be described in detail. Fig. 18 is a view in side elevation of still another modification of the motor support for a drop hammer; and Fig. 19 is a view of the same in rear elevation, showing fragmentarily the frame of the drop hammer. Fig. 20 is a fragmentary view, showing in plan a portion of the motor-supporting device of Fig. 19. Fig. 21 is a fragmentary view in rear elevation of still another modification of the motor support; and Fig. 22 is a view in side elevation of the last mentioned modification.

The general construction of board drop hammers is well known, and no attempt is, therefore, made to fully illustrate and completely describe such hammers. The invention has to do primarily with a shock-absorbing motor mounting, and in the several embodiments of the invention illustrated herein, I have shown the motor mounting yieldingly secured to the frame of the drop hammer. It may be desirable, however, to use (under certain conditions) cushioning means attached to an independent frame which is separate from the drop hammer frame. Such cushioning means may be arranged on a concrete base positioned closely to the hammer, similar to what is shown at the rear of the machine in my former application, above noted.

For the cushions, or for the means to obtain the desired cushioning effect, I prefer to use blocks of rubber of about the same quality as is generally used for automobile truck tires. Helical or elliptical springs, as well as other forms of springs, may be employed instead of rubber blocks, or in addition to such rubber blocks. Oil-filled cylinders and dash pots may also be used in this connection.

It will be noted that instead of the cus-

tomy one pair of rolls, I use two pair of board-driving rolls in the hammer. Such structure permits two rolls to be driven by one hammer, which results in a distribution of the pressure on the roll-driving worm, whereby very heavy work can be done without undue wear or injury to the gears. Of course, for lighter work one pair of rolls may be used. It will be further noted that the height of the hammer is much less than it could possibly be when large pulleys are used for driving the rolls, and in so eliminating large pulleys, the hammer can be installed in buildings where the available space is small.

The thrust of the roll-driving worm is taken in an upward direction by thrust washers which are provided in the gear box shown in Figs. 1 and 6. This self-contained construction eliminates all tendency for the hammer to be pulled from its base, as is usual when a hammer is driven with pulleys and belts from line shafting. Manifestly, for the same reason guy rods are unnecessary. The two worm wheels shown at the top of the machine, Fig. 1, are machined to the same size and with an equal number of teeth. Hence the rolls will be driven at equal speed, thus obviating the objections instant to differences in speed between the several board-elevating rolls of the hammer.

In Fig. 1 there is shown a portion of a drop hammer which extends above the floor line 2. A motor 3 is used for driving the hammer, and bolts 5 secure the motor to a platform 4. The shaft 6 of the motor extends to support 100 a fly wheel 7, the fly wheel being keyed at 8 to such shaft. A nut 9 is in threaded engagement with the shaft, and bears against a washer 10 to prevent lateral movement of the fly wheel. At 11 in bracket 12 the shaft 6 is supported. Bolts 13 secure the bracket 12 to the platform 4. A bevel gear 16 is affixed to the shaft 6, and meshes, as shown in Fig. 1, with a bevel gear 18, which latter gear is secured to shaft 21. Shaft 21 is revolvably supported in bracket 12, and at its upper end is secured to a universal joint 24.

The platform 4 is secured to two levers 26, 27 by means of bolts 13 and 28. Two opposed levers 32 and 33 are pivotally secured, intermediate their length, to the frame 39 of the drop hammer. A shaft 31, being of reduced diameter at its two end positions, interconnects the levers 26, 27, 32, 33, as shown in Fig. 1. The shaft 31 serves as a spacer for 120 the outer ends of levers 32 and 33, as well as serving for the pivotal inner connection of the four levers. Nuts 34 and washers 35 retain the levers in this assembled position, while cross rods 29 and 30 interbrace the 130 platform 4 and levers 26, 27. As shown in Figs. 6 and 7, the levers 32 and 33 are conveniently connected to the frame 39 by means of a shaft 36. The levers are keyed to shaft 36 at 58, and are laterally held thereon by 130

means of nuts and washers 37, 38. The shaft 36 is carried by the frame 39 in bearings 40 which are included in the heavy ribs 41 of the frame.

5 The lever arms 32 and 33 are held in substantially horizontal position by means of rods 42 which pass at their upper terminals through the inner ends of levers 32 and 33 and are secured at their lower terminals in 10 threaded engagement with the base of the machine at 43. A plurality of rubber blocks 44 serve as cushions between the washers 45 and the arms 32 and 33. The washers are held on the rods 42 by nuts 46. Advantageously, the rods 42 are flattened at 52 (see Figs. 6 and 9), whereby lock washers 50 in engaging the flattened portion of the rods prevent the rods from rotating out of threaded engagement at 43, and in general hold the 15 parts in their illustrated position. Rubber cushions 47 and 48 are located between levers 26 and 32 and between levers 27 and 33, as indicated in Figs. 6 and 8. These rubber cushions are wedge shaped, as shown in Fig. 8. 20 From the universal joint 24 there extends upwardly a shaft 53. The shaft 53 is pinned to the upper portion of the universal joint at 54. This universal joint 24 is not of unusual structure and will not be described 25 further.

The upper end of the rod 53 is affixed by means of a feather key 57 within sleeve 56 of a universal joint 55. Relative axial movement between the universal joint 55 and shaft 53 is permitted to accommodate the 30 vertical oscillations of the motor when the hammer head of the machine delivers a blow. Of course, the universal joints associated with shaft 53 will admit of such horizontal 35 movement of the motor 3 as the blows of the hammer head create.

The motor and motor support as a whole are borne by the shaft 36, and in Fig. 6 it will be seen that the motor is so supported 40 relatively to the shaft that its weight, as well as the weight of the links, will tend constantly to rotate the links 32 and 33 in a counter-clockwise direction. The rubber washers 44, however, are in effect a yielding stop to prevent such rotation. There is, 45 manifestly, a similar tendency for the motor and its supporting links 26 and 27 to rotate clockwise upon the shaft 31, and the rubber blocks 47 resiliently prevent such rotation. 50 Such mechanical linkage is effective to prevent the shocks which are created by the operation of the hammer from harming the motor 3. If desired, the bearings for the shaft 36 (within the ribs 41) may be of 55 resilient material, or resiliently mounted to enhance the shock absorbing characteristics of the motor support as a whole. In addition a resilient washer 60 (Fig. 7) may be interposed between the links 32 and 33 and the 60 frame 39 to cushion shocks which tend to

produce lateral movement of said links upon the supporting shaft 36.

Adjacent the top of the hammer, and within the gear box 62, there is trunnioned a worm 61. The shaft 59 of the worm is keyed to the universal joint 55, and manifestly positive connections for driving the worm are had with the motor 3. The gear box 62 is secured to drop hammer frame by means of a tongue portion 76. The shafts 78 and 80 of the two driven rolls 86 and 91 extend into the gear box 62, and therein the shafts are provided with fixed gears 82 and 83 respectively in mesh with the worm 61. In Figs. 2 and 6, I show the shaft 80 passing through top portions 84 and 85 of the hammer, and show the roll 86 keyed at 87 to said shaft. The shaft 80 also passes through a bushing 88 which permits the shaft and key to be pushed through the roll 86 before the bushing 88 is assembled. A spur gear 89 is also keyed to shaft 80 by means of a gib key 90. The shaft 78 is keyed to roll 91 in the same manner as the shaft 80 is keyed to the roll 86, and is assembled similarly by using a bushing 92 having the head 93 bearing against the portion 85 of the hammer. A spur gear 94 is keyed at 95 to shaft 78. In Fig. 2 the spur gears 89 and 94 are shown in position for driving spur gears 96 and 97 respectively, which latter gears are keyed to shafts 98 and 99. Opposed to roll 86 is a roll 104, and opposed to roll 91 is a roll 105, and the diameter of all the rolls and the gearing are such that the peripheral speeds of all the rolls are equal. As shown in Figs. 1 and 2 the shaft 98 is eccentrically mounted in shafts 108 and 110, and the shaft 99 is similarly located in eccentric bushings 107 and 109. The shafts 107, 108, 109 and 110 are rigidly connected at their inner ends to levers 111, 112, 113 and 114 respectively. These levers are respectively formed with bosses 115, 116, 117 and 118, and the upper pair of levers form bearings for a shaft 119, which shaft lies within the upper end of a rack 120.

In a similar manner a shaft 121 is arranged with a rack 122 and bosses 115 and 117. Each of said racks has a round rod solidly united with it, one rod being numbered 123 and the other 124. These rods are fitted into the larger ends of racks 122 and 120 respectively, in which racks the rods are free to slide. The said rods 123 and 124 are each provided with a nut (125 and 126) which nuts are spaced from the racks to allow a limited amount of relative sliding movement of the racks. The said racks have teeth in mesh with a small spur gear pinion 127, which pinion has shanks 128 of reduced diameter, as shown in Fig. 5. A control rod 129 includes at its upper end the forked legs 130 and 131, and the shanks 128 of the pinion 127 are retained in the legs 130 and 131 of the control rod. As indicated in Figs. 2 and 3 a bushing 132 is driven into leg 130 of the 130

control rod. The control rod 129 is connected to a lever 133 which is pivoted at 135 to operate in controlling the elevating of the board 106 and its associated hammer 137.

5 The two upper levers 112 and 114 act in unison or as a unit, and the two levers 111 and 113 also act together. These levers are connected, as said above to the two racks 120 and 122, and by means of the pinion 127, 10 with which pinion the racks are in mutual engagement, the raising or lowering of the control rod 129 will effect respectively the outward or inward movement of the rolls 104 and 105. That is to say, upon lowering 15 the control rod 129 the two pair of levers will be rotated counter-clockwise to effect the movement of the rolls 104 and 105 into engagement with the board 106. Upon the raising of the control rod, the levers will be rotated in a clockwise direction to move the rolls out of engagement with the board. So, 20 in moving the rotating rolls 104 and 105 into and out of engagement with the board 106, the hammer head of the machine may be caused to rise and fall and do its work. The 25 racks 120 and 122 with the pinion 127 will, upon downward pull of the control rod 129, equalize the pressures with which the rolls 104 and 105 engage the board 106. In Fig. 30 3 the control rod 129 is shown in its extreme upward position, and in this position the lever 133 rests upon a pin 136, the pin 136 being secured in the hammer head 137. In 35 operation the hammer head 137 and rod 129 are raised (Fig. 3) and held in such raised position by board clamps. The board clamps to which I refer are known to the art and are not shown in the drawings. Suffice it to say, 40 the board clamps are released by the operator of the machine, and so the hammer head is released to drop by force of gravity.

A modification of the hammer driving means is shown in Fig. 4. A fragmentarily indicated motor 138 has its shaft 139 keyed 45 at 141 to a bevel gear 140. A shaft 143 is aligned with shaft 139, and is revolvably supported in a bracket 144. Upon the outer end of shaft 143 is secured a fly wheel 146, and, as shown in the drawings, a bevel gear 147 50 is secured to the shaft intermediate its length. In the bracket 144 there is trunnioned the shaft 150 which has secured to its lower end a bevel gear 152 in mesh with the gears 140 and 147. The shaft 150 may be secured to a 55 universal joint, as the shaft 21 is secured to the universal joint 24, for driving the drop hammer.

In Figs. 10 and 11 is shown a modification 60 in the motor supporting and cushioning means. In such modification the levers 155 are pivotally borne upon a shaft 157, which shaft is secured to the drop hammer base 156. That is, blocks 158 are fitted into lugs 159 which are solid with the base 156, and 65 the shaft 157 extends through the blocks.

Advantageously, the blocks 158 are provided with rubber cushions 162, lying between the blocks and the lugs 159. The levers 155 rest against lugs 163, at 164. To the top of levers 155 there is attached a platform 165, and secured to this platform are four rods 167. Upon these rods there are fitted steel washers 168 and between the steel washers 168 there are interposed rubber washers 169. On top of these washers is placed a platform 170 which is formed with four holes 70 to slip over the rods 167. A gear bracket 171 and a motor 172 (both being fragmentarily indicated) are secured to the platform 170. The horizontal shocks from the hammer are 75 cushioned by the lateral yielding of the rods 167, while the vertical shocks will be absorbed by the washer assemblies 168, 169. Fig. 12 indicates a spring 174 which may serve in place of the washers 168, 169 on the 80 rods 167.

Figs. 13 and 14 illustrate another embodiment of driving mechanism which is generally similar to the mechanism shown in Figs. 1, 2, 3 and 6. The latter modified structure 90 (Figs 13, and 14) includes a lever 175 which comprises two side members integrally connected by means of a cross piece 189. A rubber block 176 is interposed between each side member of this lever and a base 177 of the 95 hammer. From said base, lugs 178 project and form a packing for each of the rubber blocks 176. In appropriate lugs 180, integral with the base 177, blocks 179 are fitted to form bearings for a shaft 181, upon which the lever 175 is pivotally secured to the drop hammer. Immediately below the shaft 181 there are pivoted two links 184, said pivotal connection being made by means of pins 185 100 extending into lugs 180. These links 184 are also pivotally connected at 186 to a member 187. Member 187 is pivotally supported by a shaft 188. Manifestly the four 105 centers of inter-connection (181, 185, 186, 188) are so disposed as to create a parallelogram hinge, and the member 187 will always remain in vertical position, irrespective of the movement of levers 175 and 184. The member 187 includes a horizontal extension 190 and, of course, the member 187 in remaining vertical position will cause the extension 190 to remain in a horizontal position. To the extension 190 there is pivotally secured at 193 110 a pair of arms 191 and 192. In the upper portion of arms 191 and 192 the shafts 195 cooperate with lugs 200 and 202 to support a platform 201. Between these lugs and the arms 191 and 192 the rubber blocks 204, having the diverging sides 205, are fitted. The 115 rubber blocks are held in place by the screws 206. The reference numerals 207 and 208 represent respectively fragments of a gear bracket and a motor which are borne by the 120 platform 201. This arrangement also pro- 125 130

vides cushioning for the driving mechanism which is carried by the platform 201, irrespective of whether the shocks are vertical or horizontal in effect, and in all positions of the motor supporting linkage the platform 201 will remain in a horizontal plane. That is to say, the arms 191 and 192 being angularly arranged with respect to the vertical, will yield upon the rubbers 204 to both horizontal and vertical shocks, and since they are pivotally secured to the extension 190, which extension will also yield to shocks (against the cushions 176), the driving mechanism, obviously, is well protected against both vertical and horizontal shocks. In Fig. 13 I show additional rubber washers 209 upon the shafts 195. These washers 209 are intended to cushion the platform from shocks which are effective in a line parallel to the axis of the shafts 195.

The modification shown in Fig. 15 indicates fragmentarily a lever 212, which lever corresponds to the lever 32 of Fig. 6. There are in fact two levers 212 which are pivotally attached and cushioned to the hammer frame 213, in a manner generally similar to that in which the levers 32 are secured to the frame 39. Figs. 15, 16 and 19 should be considered together in the following description. The floor upon which the hammer rests is indicated by the numeral 214, and numeral 215 indicates the base upon which the hammer frame 213 is secured. The lever 216 corresponds generally to the lever 26 of Figs. 1 and 6, except that it is adapted to be fastened to a cross bar 217 by means of bolts 218. The lower terminal portions of the levers 216 (there being, obviously, a pair of levers 216) are formed to support a platform 219. Fig. 16 represents fragmentarily the upper portion of levers 216 which are provided with holes 220 for the reception of a shaft, such as the shaft 31 of Figs. 1 and 6. Upon the middle portion of cross bar 217 lugs 221 are formed. Between these lugs 221 there is pivotally secured upon a pin 223 a link 222. The other end of the link 222 is pivoted to the lugs 224 which are integral with the machine frame. It may be remarked that the horizontal and perpendicular planes passing through the centers of the pins (226, 220, 225 and 223) of the pivotal interconnection of the linkage form a parallelogram, and the levers 216 will always remain in a vertical position. The levers 216 are formed each with a leg 227 which extends therefrom in a horizontal plane. To these legs there are loosely pivoted the arms 228 and 229, and these arms are maintained in a vertical position by means of rubber blocks adjacent their upper ends. As shown in Figs. 19 and 20, a rubber block 232 is held between a lug 233, a projecting part of the leg 227, and the arm 228. Similarly, the rubber blocks 234, 235, 236 and 237 are positioned in the leg 227. Fig. 20 illus-

trates in plan a portion of the horizontal leg 227; that is, before the platform 219 has been mounted thereon. As shown in Figs. 18 and 19, special washers 239 hold all the rubber blocks in place. The upper portions of arms 228 and 229 (Fig. 19) are loosely fitted to turn upon pins 241 and 242, which pins are driven into lugs 243 and 244 of the platform 219. Due to the aforesaid parallelogram arrangement of the motor-supporting linkage, the platform will always remain in a horizontal plane. In view of the fact that the fixed centers of pins 230 and 231 lie in a horizontal plane which is parallel to legs 227, and since the centers of pins 241 and 242 are respectively arranged at equal intervals of space from the centers 231 and 230, the said four centers must always be in the lines of intersection of parts which form a parallelogram. The platform 219 will always lie in a horizontal plane, regardless of the movements of the arms 228 and 229.

Figs. 21 and 22 show a still further modification of the motor-supporting device of my invention. The lever 245, which corresponds to the lever 175 of the device illustrated in Fig. 14, includes two end members which are pivotally connected by means of a shaft 247 to the lever 246. The lever 245 is secured to the frame of the drop hammer in a manner similar to that in which the lever 175 is secured, and the lever 246 is attached to the lever 245, as the member 187 is attached to the lever 175. As shown in Fig. 21, the lever 246 includes an angular extension 250, to which extension four arms 248 are pivotally secured at 249. To the lower end of levers 248 there is connected on pins 252 a motor-supporting platform 251. Here again the platform forms with its supporting linkages a parallelogram, and obviously the platform will always remain in a horizontal plane, regardless of its swinging motion about the points 249. Such linkage permits the platform 251 (the connections at 249 being loose) to yield to horizontal shocks. A motor 253 and a gear bracket 254 are secured to the platform 251, and suitable connections, such as those shown in Fig. 1, are made to the roll-operating means of the hammer. The linkage shown in Figs. 21 and 22 is provided with cushioning means to absorb vertical shocks by means of rubber blocks; that is, blocks such as the blocks 176 (Fig. 14) are organized with the levers 246.

What I claim is:

1. A motor support comprising a supporting frame, lever arms pivotally mounted in said frame, cushioning means interposed between said arms and said frame, a motor supporting platform, supporting arms pivotally connecting said platform with the lever arms in said frame, and cushioning means interposed between said platform and supporting arms.

2. A yielding motor support comprising a frame, lever arms pivotally mounted in said frame, tension members secured in said frame and maintaining said lever arms in substantially fixed position with respect to said frame, yielding means between said tension members and said lever arms, a motor supporting platform, supporting arms pivotally connecting said platform with the lever arms in said frame, and cushioning means interposed between said platform and the supporting arms connected thereto.
3. A yielding motor support comprising a frame, a lever arm pivotally mounted in said frame, a motor-supporting member, means pivotally suspending said motor-supporting member from said lever arm at a point removed from the pivotal mounting of the lever arm, a stop on said frame arranged to limit positively angular movement of said lever arm under the weight of said motor-supporting member, and cushioning means effectively disposed between said lever arm and said stop.
4. A motor mounting comprising a frame, a lever pivotally connected to said frame, a motor-supporting member borne by connections to said lever, said connections joining the lever at a point remote from the pivotal connection of said lever to the frame, which motor-supporting member by reason of its weight and location with respect to said pivotal connection tends constantly to produce angular movement of said lever, together with means for yieldingly resisting and positively preventing such angular movement.

In testimony whereof I affix my signature.
JOHN NIVER SCISM.
